(57) **CLAIM**

The ornamental design for a germination cover with bracket as shown and described.

DESCRIPTION

FIG. 1 is a perspective view of a germination cover with bracket showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged detail view taken from portion 8 of FIG. 7.

The dot-dash lines indicate cutoff boundaries for enlarged detail portion views and form no part of the claimed design.
